ROTARY CUTTER HEAD FOR SEWER RODS

Anton P. Kjerulff, Lake Charles, La.

Application June 30, 1945, Serial No. 602,610

1. Claim. (Cl. 15—104.3)

1

This invention relates to sewer rods.

An object of the invention is the provision of a head for sewer rods, in which cutters are rotatably mounted on a support in such a manner that portions of the periphery of the cutters will be substantially in contact with each other so that the inner faces of the cutters will form an acute angle with each other.

Another object of the invention is the provision of a head for sewer rods in which a triangularly shaped support has a pair of inclined side walls with the inner flat faces of roller cutters being mounted on the side walls so that portions of the peripheries of the cutters will be substantially in contact at the outer end of the head, the support and rod having cooperating means for connecting the support to the rod, said support being provided with inwardly disposed stationary cutters having round sharpened edges facing rearwardly for cutting roots or other matter which clog the sewer.

A further object of the invention is the provision of a head for sewer rods in which a triangularly shaped support has mounted on the side edges thereof, cutters provided with circular flat inner faces inclined at an angle to each other with portions of the peripheries of the flat faces being substantially in contact at the outer end of the head, the outer faces of the cutters being sections of a sphere or variations thereof, a hollow shank projecting inwardly from the base of the support and provided with stationary cutters extending radially therefrom with the inner edges of the cutters being curved and sharpened, a rod having a reduced portion received within the hollow shank with means for removably connecting the reduced portion to the support, said support being provided with cutters extending rearwardly toward the rod and penetrating an obstruction in the sewer so that it may be removed from the sewer when the rod is withdrawn from the sewer.

This invention will be best understood from a consideration of the following detailed description, in view of the accompanying drawings forming a part of the specification; nevertheless, it is to be understood that the invention is not confined to the disclosure, being susceptible of such changes and modifications as define no material departure from the salient features of the invention as expressed in the appended claim.

In the drawings:

Fig. 1 is a plan view partly in section of a sewer head constructed according to the principles of my invention.

2

Fig. 2 is a view similar to that shown in Fig. 1, but turned at 90° to said view.

Fig. 3 is a modified form of connecting member between the rod and the head.

Fig. 4 is a plan view of a further modified form of the head, partly in section.

Referring more particularly to the drawings, Figs. 1 and 2, 10 designates a triangularly shaped support which has a base portion 11 and side 10 walls 12 inclined toward each other and terminating in a rounded apex 13. In other words, the support 10 is an open framework.

Each inclined side wall 12 of the support has mounted thereon an approximately semi-spherically shaped cutter 15 with the inner circular flat face 16 in engagement with a side wall or bar of the support. An axle 17 is received by an axially disposed passage 18 in the cutter 15. The axle has reduced portions 19 and 20 respectively, 20 at its inner and outer ends. The reduced portion 19 passes through the perforations 21 in a bar 12 while the reduced portion 20 passes through a central opening in a washer 22. The outer ends of the reduced portions are swaged 25 over to maintain the roller 15 in position. The disposition of the rollers maintains portions of the peripheries of the inner faces of said rollers or cutters in substantial contact as shown at 23. The mounting of these cutters is such that they 30 will freely revolve on the axle 17 when the head is being forced through a sewer.

A hollow shank, generally designated by the numeral 25, extends through and is rigidly connected to the base 11 of the support 10. Surrounding its projecting end and lying against the inner face of the base 11 is a ring or washer 26 which is held in place in such a manner as to allow the head to freely rotate.

A pair of stationary cutters 30 are secured to the side walls of the shank or sleeve 25 and are diametrically disposed with respect to each other. The inner edge of each cutter is rounded and sharpened as shown at 31. The cutters 30 act as guards for the rear edges of the cutters 15 so that when the head is being withdrawn it will not be hung up on sharp edges or defects on the inner surfaces of sewer pipes.

At the forward end of the sewer rod is a connecting member 32 having a shoulder 33 engaging the outer or rear end of the sleeve 25 and a cylindrical portion which extends through and projects beyond the inner end of the sleeve where it is provided with a transverse perforation which receives a cotter pin or wedge 36. The latter bears against the inner end of the

sleeve 25, free of the washer 26, for maintaining the support 10 but leaving it free to rotate on the connecting member 32.

A bar 40 extends from the shoulder 33 and is offset with respect to the longitudinal axis of the pin 34. This flat bar is provided with perforations alined with perforations on the outer flat end 41 of a sewer rod 42. Bolts 43 are received by the alined perforations in members 40 and 41, and nuts 44 draw the bolts up tight for securing the head to the sewer rod 42.

Inspection of the cutters 15 will show that they are formed by a plane cutting a sphere or spheroid at points between a pole and the center of the sphere to form a section which is less than a hemisphere in order to provide sharp cutting surfaces for the members 15 along their peripheries.

An inspection of Fig. 1 will show that the inner flat surfaces 16 of the cutters 15 are located at such an angle that the outer curved surfaces 24 of the cutters almost form a perfect circle where the outer ends of the cutters are associated as shown at 23, so that the head appears slightly pointed whereby the head may be readily pushed around bends and through obstructions in a sewer, with the sharp cutting edges of the members 15 set at divergent angles in order to cut grease and the other obstructions.

The connections between the member 32 and the support 10 is such that the head is swiveled on the connecting member 32 and is free to rotate thereon. In other words, the wedge 36 will maintain the head on the member 32, but will not bind the sleeve 25 to the pin 34.

The blades 30 are not only welded to diametrically opposite points on the sleeve 25, but the outer ends of these blades are likewise welded to the inner face of the base 11 of the support 10. These blades not only form knives for cutting through obstacles when the head is withdrawn, but they serve to reinforce the connection between the sleeve 25 and the base 11 of said support. If desired, the sharp cutting edges 31 may be omitted, still allowing the blades to act in guiding the head when being withdrawn around pipe bends or obstructions on which the rear edges of the cutters might engage.

The construction shown in Fig. 3 is substantially identical with that shown in Figs. 1 and 2, except that a modified form of the connecting head member for the sewer rod is employed.

In Fig. 3 I have shown a simplified means of attachment between the sewer rod and the head which differs from that previously described in that provision for the swiveling action of the head is omitted. In this structure the base 11 of the support is slotted centrally to receive a

finger 47 on the plate 48. The latter has wings 49 abutting and welded to the underside of base 11 the edges 50 of which are curved and sharpened, their outer points lying in a position to guard the contiguous edges of the cutters 15 when the head is being withdrawn. A tail piece 51 on plate 48 provides means of attachment to the sewer rod 42, as by means of bolts 52.

In the modification illustrated in Fig. 4, I have shown frusto-conically shaped cutters 60 rotatably mounted on axles 67, carried by the inclined side walls 62 of a support 63. The peripheral edges 61 of these cutters are particularly sharp due to the shape of the cutters. As in the modification shown in Fig. 1, the blades 30 are attached to the base portion of the support 63 by welding, as indicated at 67.

The swivel mounting for the head comprises the pin in the sleeve the former having the enlarged threaded end 64 adapted to be screwed into a complementary socket on one end of a spiral or coil spring sewer rod, as will be understood.

It will be understood that the different forms of cutters which are used on the heads may be employed alternately as conditions encountered in different operations may require.

I claim:

A head for sewer rods comprising a triangularly shaped support, a circular roller having a cutting edge at its periphery and rotatably mounted on each side of the support so that portions of the cutting edges of the rollers will always be in substantial contact with each other forwardly of the support, a collar extending through the base portion of the triangularly shaped support and a blade secured to the rearward side of said base portion and extending to said cutting edges at their rearward portion.
